(57) **CLAIM**
The ornamental design for a head detail, as shown and described.

DESCRIPTION

FIG. 1 is a rear elevation view of a head detail;
FIG. 2 is a top plan view thereof;
FIG. 3 is a front elevation view thereof;
FIG. 4 is a right side elevation view thereof;
FIG. 5 is a left side elevation view thereof; and,
FIG. 6 is a perspective view thereof.

The ornamental design of a head detail pertains to elongated plaster moldings designed to run between a ceiling and a floor and having an abutment surface for abutment against the end surface of a partition wall or as a join between two such walls.
